UNITED STATES PATENT OFFICE.

VERNIE LOCKWOOD, OF MOTLEY, MINNESOTA.

STAY AND FASTENER FOR STORM-SASH.

1,139,781.

Specification of Letters Patent. Patented May 18, 1915.

Application filed May 11, 1914. Serial No. 827,645.

To all whom it may concern:

Be it known that I, VERNIE LOCKWOOD, citizen of the United States, residing at Motley, in the county of Morrison and State of Minnesota, have invented certain new and useful Improvements in Stays and Fasteners for Storm-Sash; and I do hereby declare the following to be a full, clear, and exact description of the invention, such as will enable others skilled in the art to which it appertains to make and use the same.

My invention has for its object to provide an improved stay and fastener, especially adapted for use on storm sash, for holding the same in different open positions or in a closed position; and, to this end, generally stated, the invention consists of the novel devices and combinations of devices herein-after defined and described in the claims.

In the accompanying drawings, which illustrate the invention, like characters indicate like parts throughout the several views.

Referring to the drawings, Figure 1 is a perspective view showing the improved stay and fastener applied in working position to a window frame and storm sash; Fig. 2 is an edge elevation of the improved stay and fastener removed from the window frame and sash; Fig. 3 is a side elevation of the improved stay and fastener, on an enlarged scale, some parts being broken away; Fig. 4 is a side elevation of the so-called frame bracket; and Fig. 5 is a side elevation of the end of the improved stay, which is pivotally secured to the said frame bracket.

The numerals 1 and 2 indicate, respectively, a window frame and a lower sash, mounted in said frame for vertical sliding movement. The customary storm sash is hinged at its upper end to the window frame 1 for outward swinging movement.

The improved stay is in the form of a toggle and the members thereof are indicated by the numerals 4 and 5. The free end of the toggle member 4 is pivotally secured to a bracket 6, secured by screws to the lower rail of the storm sash 3. This bracket 6 is provided with a finger piece 7 by which the storm sash 3 may be moved to and from a closed position. The free end of the toggle member 5 is pivotally secured by a thumb nut equipped bolt 8, to a bracket 9, screwed to the window sill. By means of the bolt 8, the toggle member 5 may be frictionally clamped to the bracket 9 in differ-

ent angular adjustments so as to hold the storm sash 3 open in different positions. To prevent any tendency of the toggle member 5 from slipping with respect to the bracket 9, said toggle member and bracket are corrugated at 10, and when clamped together by the bolt 8 the corrugations of the one will fit within the corrugations of the other.

To lock the storm sash 3 closed, the free end of the toggle arm 4 is notched at 11 so as to embrace the bolt 8 when the members of the toggle are folded together. The free end of the toggle member 4 is also laterally offset from the toggle member 5 so that when said toggle members are folded together they will embrace the bracket 9. By tightening the bolt 8 both members of the toggle may be frictionally clamped onto the bracket 9, which projects therebetween, thus locking the storm sash 3 closed. In the drawings, the bracket 9 is provided with an entrance passage 12, which extends into the opening into which the bolt 8 extends and pivotally works. This opening permits the bolt to be moved laterally from the bracket 9, thus disconnecting the toggle when the storm sash is removed from the window frame. This opening into the bracket 9, however, is not absolutely necessary as the bolt 8 can be removed endwise from said bracket by removing the thumb nut. When the storm sash 3 is removed from the window frame, the entire stay and fastener, with the exception of the bracket 9, is removed with said sash. The bracket 9 remains permanently on the window sill.

The above described device, while extremely simple and of small cost to manufacture, is thought to be highly efficient for the purpose had in view.

What I claim is:

1. The combination with a window frame and sash, the latter being hinged to the former, of a frame bracket and a sash bracket, secured, respectively, to said frame and sash, a toggle, one member of which is pivotally secured to said sash bracket, and a clamp pivotally connecting the other member of said toggle to said frame bracket, in different angular adjustments, to hold said sash open, and for clamping the outer ends of both members of said toggle to said frame bracket, for holding said sash closed.

2. The combination with a window frame and sash, the latter being hinged to the former, of a frame bracket and a sash bracket,

secured, respectively, to said frame and sash, a toggle, one member of which is pivotally secured to said sash bracket, and a clamp pivotally and detachably connecting the other member of said toggle to said frame bracket, in different angular adjustments, to hold said sash open, and for clamping the outer ends of both members of said toggle on opposite sides of said frame bracket, for holding said sash closed.

3. The combination with a window frame and sash, the latter being hinged to the former, of a frame bracket and a sash bracket, secured, respectively, to said frame and sash, a toggle, one member of which is pivotally secured to said sash bracket, and a thumb-

nut-equipped bolt pivotally and detachably connecting the other member of said toggle to said frame bracket, in different angular adjustments, to hold said sash open, and for clamping both members of said toggle to said frame bracket, for holding said sash closed, the member of said toggle which is pivoted to said sash bracket having a notch embracing said bolt, when said sash is closed.

In testimony whereof I affix my signature in presence of two witnesses.

VERNIE LOCKWOOD,
